(57) **CLAIM**

The ornamental design for a portable tea set, as shown and described.

DESCRIPTION

FIG. 1 is a front elevational view of a portable tea set showing our new design;

FIG. 2 is a rear elevational view thereof;

FIG. 3 is a left side view thereof;

FIG. 4 is a right side view thereof;

FIG. 5 is a top plan view thereof;

FIG. 6 is a bottom plan view thereof;

FIG. 7 is a perspective view thereof; and,

FIG. 8 is a perspective view thereof, shown assembled and in a configuration of use.

The portions of the portable tea set shown in broken line form no part of the claimed design.

1 Claim, 8 Drawing Sheets(56)
